UNITED STATES PATENT OFFICE

HENRI LOUIS JOSEPH HAQUIN, OF VOYENNE, FRANCE

INSULATOR AND MOLD FOR CASTING THE SAME

Application filed March 15, 1928, Serial No. 261,793, and in Belgium October 10, 1927.

The present invention relates to insulators and molds for casting the same.

Up to the present time, it has been found impossible to produce cast glass insulators having an internal loop formed integrally therewith of the type generally provided in porcelain insulators.

One of the objects of the invention is to provide a modified form of insulator which permits a casting operation to be effected.

Another object is to provide a special form of mold designed to produce the above mentioned modified form of insulator.

Still further objects will appear in the course of the detailed description now to be given with reference to the accompanying drawings, in which:—

Fig. 1 is a section through the ordinary form of porcelain insulator now in current use;

Fig. 2 is a section through a form of insulator constructed in accordance with the present invention;

Fig. 3 is a view of the finished insulator as seen in transparent perspective;

Fig. 4 represents a mold, in section, designed to produce an insulator of the type shown in Fig. 2;

Fig. 5 is a section taken on line 5—5 of Fig. 4;

Fig. 6 illustrates the various mold closure devices in plan.

Fig. 7 shows, in perspective, the mold and core sections in separated position;

Figs. 8 and 9, illustrate, in the same manner as Figs. 4 and 5 a different form of mold assembly.

Referring to Fig. 1 of the drawings, there is shown the usual form of porcelain insulator having an external portion AB and a "loop" portion N. The center of curvature C of surface AB is generally placed substantially at or below the surface of "loop" L, thus making it difficult or impossible to move properly shaped cores into, and out of,

the spaces constituting the hollow portions of the insulator.

To overcome this difficulty, the shape of the insulator has been modified in the manner shown in Fig. 2. Here "center of curvature" C is placed outside of "loop" surface L and AB is given the form (1) of a spherical surface of radius CM, or (2) of a surface whose radius increases as CM moves away from point A. The reasons for this choice of curvature will appear in the course of the description to be given of the special cores used in the casting operation. It is to be noted further that the section of the "loop" is here modified so that distance CN¹ either remains constant or, gradually decreases in the course of the movement of point N¹ from A¹ to B¹.

Referring now to Figs. 3 to 5 of the drawings, representing the special mold for casting the above described insulator, there is shown a two part mold a, a arranged to slide in guideways t, t and having a cavity b and a cavity c formed therein corresponding to the shape of the insulator shown in Figs. 2 and 3. Cavities b and c form the walls of the criss-cross internal passages extending through the insulator at right angles to one another (Fig. 3). The hollow portions of the molded article or casting are formed in part by a two part core d, d hingedly mounted on a pair of shafts f, f and arranged to be moved into and out of the mold cavity by means of a pair of suspension rods o, o, pivotally mounted on a double lever m, m, fulcrumed at n and counterbalanced at p. Stops q limit the downward movement of lever m and core d, d while handles k, k permit either core section to be rotated out of the mold. It will now be evident why the special curvatures of the insulator shown in Fig. 2 were given the values indicated. Inasmuch as core sections d must be removed by rotation, the curvatures of the skirt and of the loop portions of the mold and of the insula-

tor must be chosen so as to permit such a movement to be effected, i. e. the axis of rotation of shafts f , f , should correspond to the position of point C of Fig. 2. The mold is completed by a top closure h formed (1) of one or more circular segments held in place by bolts i as shown in Figs. 4 and 5 or (2) of a pair of segments hinged at h^1 and locked together at their free extremities by any convenient device engaging either directly with each segment or coacting with handles i^1 , i^2 (Fig. 6). To assure core d , d being securely locked in place, a bar s may be wedged into place between handles k , k and ring h (1) 5 may be made sufficiently wide to overlap the top of the core surface, or (2) it may be fitted with L-shaped bars u arranged to be held firmly against the core by bolts i as shown in Fig. 5, or again (3) it may be provided with 10 tenons v , v adapted to engage in proper recesses formed in the core sections as shown in Fig. 6.

The manner in which the device operates is practically evident from the foregoing 25 description. Core sections d , d are first lowered into place; bar s is then applied so as to bring the core surfaces into contact at g and ring h is mounted in position. After the charge has been poured through gate r , 30 the core is lifted out and mold sections a , a moved apart or conversely.

In the form of mold shown in Figs. 8 and 9, the core sections, instead of being mounted above the mold sections are placed below the 35 latter. This mold assembly functions in substantially the same manner as the one shown in Fig. 4 and 5 except that, in opening the mold, it is advisable to first move apart the mold sections and to then remove the cores.

40 It is to be noted that in the insulator, the novel form has been chosen mainly in view of facilitating the casting operation and that the specially designed mold is particularly adapted to the molding of articles having the 45 contours and presenting the casting problem peculiar to insulators of the type described.

What I claim is:—

1. A mold assembly comprising in combination a pair of mold members adapted to be moved towards and away from one another, said mold members having a molding cavity formed therein whose surface includes a bridge-like portion extending between two 50 parts thereof, and a pair of bent core members pivotally mounted on a common axis, said core members when inserted in operative position in the mold cavity passing under said bridge-like portion of the latter and contacting thereunder.

2. A structure as defined in claim 1 in combination with means for locking said cores in operative position in the mold cavity.

3. A structure as defined in claim 1 in combination with means for locking said cores

in operative position in the mold cavity, and means independent of the mold members for supporting the cores.

4. A structure as defined in claim 1 in combination with a handle rigidly mounted on each core, and a locking bar extending between said handles and tending to force the latter apart.

In testimony whereof I have hereunto set my hand.

HENRI LOUIS JOSEPH HAQUIN.
